UNITED STATES PATENT OFFICE.

CHRISTIAN CHRISTIANSEN, OF KENMAR, NORTH DAKOTA.

STARTING MECHANISM FOR EXPLOSION-ENGINES.

1,010,233.

Specification of Letters Patent. Patented Nov. 28, 1911.

Application filed February 6, 1911. Serial No. 606,987.

To all whom it may concern:

Be it known that I, CHRISTIAN CHRISTIANSEN, a citizen of the United States, residing at Kenmare, in the county of Ward 5 and State of North Dakota, have invented certain new and useful Improvements in Starting Mechanism for Explosion-Engines; and I do declare the following to be a full, clear, and exact description of the invention, such as will enable others skilled in the art to which it appertains to make and use the same.

This invention relates to improvements in starting mechanism for explosive engines.

One object of the invention is to provide a spring actuated starting mechanism adapted to be operatively connected with the crank shaft of the engine whereby the engine may be started independently or 20 without interfering with the usual crank operated starting mechanism.

Another object is to provide a mechanical or spring actuated starting mechanism adapted to be wound up or set by the operator without leaving his seat.

With the foregoing and other objects in view the invention consists of certain novel features of construction, combination and arrangement of parts as will be more fully 30 described and particularly pointed out in the appended claims.

In the accompanying drawings; Figure 1 is a front view of the forward end of an automobile showing the application of the 35 invention thereto; Fig. 2 is a top plan view of the same; Fig. 3 is a central vertical longitudinal section; Fig. 4 is a vertical cross section on the line 4—4 of Fig. 2; Fig. 5 is a horizontal sectional view on the 40 line 5—5 of Fig. 3.

Referring more particularly to the drawings, 1 denotes the front end of the supporting frame of an automobile and 2 denotes the dash board.

45 Revolubly mounted in suitable bearings on the frame 1 is the projecting outer end of the engine shaft 3 on which is fixedly mounted one member 4 of a clutch, said member comprising a socket having arranged transversely therethrough a pin 5 the ends of which project beyond the opposite sides of the socket as shown. Revolubly mounted in suitable bearings on the outer end of the frame 1 is the usual starting 50 shaft 60 provided with a cranking handle 6 on the inner end of which shaft is arranged

a clutch member 7 comprising a cylindrical block having formed therein a transverse notch 8 which when the handle 6 is pushed inwardly will engage the portion of the pin 5 within the socket or clutch member 4 thereby operatively connecting said handle with the engine shaft 3. The shaft 60 is normally retracted to hold the clutch member 7 thereon out of engagement with the clutch member 4 by a coiled spring 9. Arranged on the forward end of the frame 1 is an upwardly projecting gear supporting frame 10 in the upper end of which is slidably mounted a horizontally disposed bearing frame 11 said frame having in its opposite ends guide notches 12 which engage the parallel vertical upper portions of the side bars of the frame 10. The bearing frame 11 is adjustably supported in the upper portion of the frame 10 by adjusting screws 13 arranged in the upper cross bar of the frame 10 as shown. Revolubly mounted in the frame 11 is a short gear supporting shaft 14 on which is fixedly mounted a spur gear 15 and a sprocket gear 16. The sprocket gear 16 is connected by a sprocket chain 17 with a sprocket gear 18 revolubly mounted on the inner portion of the cranking handle 6 adjacent to the clutch member 4 on the end of the engine shaft. On the hub of the sprocket gear 18 is arranged a clutch member 19 in the form of a sleeve which fits over and loosely engages the adjacent end of the clutch member 4 90 and has formed in its inner edge a series of ratchet teeth 20 which are adapted to engage the radially projecting ends of the clutch pin 5 when the sprocket gear 18 and clutch member 19 are shifted inwardly on the end of the cranking handle thereby operatively connecting the gear 15 with the engine shaft. Secured to the under side of the bearing frame 11 is a transversely disposed bar or plate 21 in which are formed 100 passages through which the opposite sides of the sprocket chain 17 pass. To the lower side of the plate or bar 21 and communicating at their upper ends with said passages are vertically disposed tubes 22 22^a in which and around the opposite sides of the chain are arranged coiled springs 23. One of the springs 23 is connected at its upper end to the portion of the chain passing therethrough while the other spring is connected 105 at its lower end to the portion of the chain passing through the same. The tube 22

having the spring which is connected at its lower end to the chain has formed in its upper end a stop flange 24 which is adapted to be engaged by the upper end of the 5 spring therein while the opposite tube 22 having the spring which is connected at its lower end to the chain has formed in its upper end a stop flange 25 adapted to be engaged by the lower end of the spring therein. 10 By thus arranging the springs and tubes both of the springs will be compressed by the movement of the chain through the tubes thus providing power whereby when the chain is released the pressure of the 15 springs will be applied to revolve the parts driven by the chains in a reverse direction thus utilizing the power of the springs to revolve the engine shaft when the clutch member 19 on the sprocket gear 18 is engaged with the clutch member on said shaft.

In order to revolve the gear 15 and thereby turn the chain in the proper direction for compressing the springs in the tubes 22 22^a I provide an operating shaft 26 which is 25 preferably formed in two sections connected together near its outer end by a universal joint 27. The inner end of the shaft 26 is slidably and revolvably mounted in a suitable bearing in the dash board of the automobile 30 while the outer end of said shaft is slidably and revolvably mounted in the bearing frame 11. The inner end of the shaft 26 is squared and on said squared end is operatively mounted a hand wheel 28 and on said end of the shaft adjacent to the wheel 28 is arranged a push button or knob 29 the purpose of which will be hereinafter described. On the portion of the shaft 26 in the bearing frame 11 is fixedly mounted a pinion 30 40 which is normally adapted to mesh with the gear 15 whereby when the shaft 26 is revolved the motion thereof will be imparted through the pinion 30 and gear 15 to the sprocket gears and chains thus turning the 45 latter in the proper direction for compressing the springs. The shaft 26 when thus operated is locked or held against retrograde movement and the springs thus held in a compressed condition by means of an 50 elongated ratchet gear 31 fixedly mounted on the shaft 26 adjacent to the pinion 30 and with which is engaged a spring pawl 32 secured to the adjacent end of the bearing frame 11. The pawl 32 is held down 55 in operative engagement with the teeth of the ratchet gear by a coiled spring 33 arranged on one of the adjusting screws 13, said screw also passing through the pawl and holding the latter in place. The shaft 60 26 is normally held in a retracted position to engage the pinion 30 with the gear 15 by a coiled spring 34 arranged between the inner side of the bearing frame 11 and a stop formed by the universal joint connection between the sections of the shaft as

shown. When it is desired to release the chain to permit the spring to actuate the cranking mechanism the knob or button 29 on the inner end of the shaft 26 is pressed and the shaft thus forced outwardly against 70 the pressure of the spring 34 until the pinion 30 is disengaged from the gear 15 whereupon the springs 23 will act to rapidly revolve the sprocket gear 18 and clutch member 19 the motion of which will be 75 imparted to the engine shaft when said clutch member is engaged with the clutch member on the end of said shaft.

In order to engage the clutch member 19 with the clutch member 4 on the engine 80 shaft simultaneously with the releasing of the springs I provide a clutch shifting lever 35 which is fulcrumed intermediately of its ends on the front side of the frame 10 and has a bifurcated lower end which engages 85 the hub of the sprocket gear 18. The upper end of the lever is flattened and disposed in position to be engaged by the outer end of the shaft 26 when the latter is projected by the knob or button 29 thereby rocking the 90 lever, at the same time that the pinion 30 is disengaged from the gear 15, and connecting the sprocket gear 18 with the engine shaft. Around the flattened upper end of the clutch shifting lever 35 is arranged a 95 guard 36 which limits the outward movement of the shaft 26 and upper end of the lever.

By providing the springs 33 and the 100 means for compressing the same as herein shown and described it will be seen that power may be provided for starting the engine and that the mechanism may be operated from the front side of the machine and may be kept in readiness to start the 105 engine at a moment's notice. It will be also noted that if the first action of the springs fails to start the engine that they may be repeatedly compressed and the power there-of applied to the engine shaft without the operator leaving the machine. By adjustably securing the bearing frame 11 in the frame 10 the chain may be adjusted and any unnecessary slack therein readily taken up. By constructing the clutch mechanism 110 between the cranking shaft and the sprocket gear, and the adjacent end of the engine shaft as herein shown and described the operation of the crank handle will not interfere with the spring actuated cranking mechanism or the latter with the hand cranking mechanism.

From the foregoing description taken in connection with the accompanying drawings, the construction and operation of the invention will be readily understood without requiring a more extended explanation.

Various changes in the form, proportion and the minor details of construction may 120 be resorted to without departing from the 125 130

principle or sacrificing any of the advantages of the invention as defined in the appended claims.

Having thus described my invention, 5 what I claim is:

1. In an engine starting mechanism, the combination with the engine shaft and a clutch member thereon, of a cranking shaft, a clutch member on the cranking shaft to 10 engage the clutch member on the engine shaft, a hand wheel shaft parallel with the cranking shaft, a gear connection between the hand wheel shaft and the cranking shaft including a gear wheel slidably journaled on 15 the cranking shaft, a clutch member carried by said gear wheel to engage the clutch member on the engine shaft, and a spring operating to normally disengage the two clutch members carried by the cranking 20 shaft from the clutch member on the engine shaft.

2. In an engine starting mechanism, the combination with the engine shaft of a clutch member fixed thereon, a cranking 25 shaft having on its inner end a clutch member adapted to engage the clutch member on the engine shaft whereby the latter may be operated by the cranking shaft, a sprocket gear loosely mounted on the cranking shaft, a clutch member on the sprocket gear to 30 engage the clutch member on the engine shaft whereby the latter may be operated by the sprocket gear, and a spring normally holding the clutch members on the cranking 35 shaft and sprocket gear out of engagement with the clutch member on the engine shaft.

3. In an engine starting mechanism, the combination with the engine shaft of a clutch member fixed thereon, a cranking 40 shaft having on its inner end a clutch member adapted to engage the clutch member on the engine shaft whereby the latter may be operated by the cranking shaft, a sprocket gear loosely mounted on the crank shaft, a clutch member on the sprocket gear to 45 engage the clutch member on the engine shaft whereby the latter may be operated by the sprocket gear, a spring normally holding the clutch members on the cranking shaft 50 and sprocket gear out of engagement with the clutch member on the engine shaft, a revolvably mounted gear supporting shaft, a sprocket gear fixed thereon, a sprocket chain connecting it with the sprocket gear on the 55 cranking shaft, coiled springs surrounding the two stretches of the chain, and connections whereby both springs are compressed when the chain moves in one direction to store their power to drive the chain in the 60 opposite direction.

4. In an engine starting mechanism, the combination with the engine shaft, of a clutch member fixed thereon, a cranking shaft having on its inner end a clutch member adapted to engage the clutch member on

the engine shaft whereby the latter may be operated by the cranking shaft, a sprocket gear loosely mounted on the cranking shaft, a clutch member on the sprocket gear to engage the clutch member on the engine shaft 70 whereby the latter may be operated by the sprocket gear, a spring normally holding the clutch members on the cranking shaft and sprocket gear out of engagement with the clutch member on the engine shaft, a revolvably mounted gear supporting shaft, a sprocket gear fixed thereon, a sprocket chain connecting it with the sprocket gear on the cranking shaft, fixedly mounted tubes arranged around the opposite sides or stretches 75 of the chain, a stop flange arranged in the upper end of one of the tubes and in the lower end of the opposite tube, springs arranged in the tubes, one of the springs being connected at its upper end to one side of 80 the chain and adapted to be engaged at its lower end with the stop flange in the lower end of said tube, the other spring being connected at its lower end with the other side of the chain and adapted to be engaged at 85 its upper end with the stop flange in the upper end of its tube whereby when the chain is moved by the sprocket gears, the springs will be compressed in the tubes, means whereby the sprocket gears are operated to compress the springs, means whereby the springs are released and the power therefrom applied to drive the sprocket gears in a reverse direction, and means to shift the sprocket gear on the cranking shaft 90 to engage the clutch member thereon with the clutch member on the engine shaft whereby the reverse movement of the sprocket gears is applied to start the engine. 95

5. In an engine starting mechanism, the combination with the engine shaft of a clutch member fixed thereon, a cranking shaft having on its inner end a clutch member adapted to engage the clutch member on the engine shaft whereby the latter may be operated by the crank handle, a sprocket gear loosely mounted on the cranking shaft, a clutch member on said sprocket gear to engage the clutch member on the engine shaft 100 whereby the latter may be operated by said sprocket gear, a spring normally holding the clutch members on the cranking shaft and sprocket gear out of engagement with the clutch member on the engine shaft, a revolvably mounted gear supporting shaft, a 105 sprocket gear fixed thereon, a sprocket chain connecting it with the sprocket gear on the cranking shaft, operating springs connected to said chain and adapted to be compressed 110 whereby when the chain is moved in one direction, a spur gear fixedly on the supporting shaft, a revolvably mounted operating shaft, a pinion fixed on said shaft to engage said spur gear, a hand wheel arranged on 115 said shaft within convenient reach of the 120

125

130

operator, means to lock said shaft against retrograde movement, means whereby the pinion thereon is disengaged from said spur gear and means whereby the sprocket gear 5 on said crank handle is shifted to engage the clutch member thereon with the clutch member on the engine shaft.

6. In an engine starting mechanism, the combination with the engine shaft of a 10 clutch member fixed thereon, a cranking shaft having on its inner end a clutch member to engage the clutch member on the engine shaft whereby the latter may be operated by the crank handle, a sprocket gear 15 loosely mounted on the cranking shaft, a clutch member on the sprocket gear to engage the clutch member on the engine shaft whereby the latter may be operated by the sprocket gear, a spring normally holding 20 the clutch members on the cranking shaft and sprocket gear out of engagement with the clutch member on the engine shaft, a gear supporting frame, a bearing frame slidably and adjustably mounted in the supporting 25 frame, a gear shaft revolvably mounted in the bearing frame, a sprocket gear on said shaft, a sprocket chain to connect this gear with the sprocket gear on the cranking shaft, springs connected to the opposite sides of 30 the chain and adapted to be compressed by the movement of the chain in one direction whereby when said springs are released the force thereof will drive the chain and sprocket gear in the opposite direction, a 35 gear wheel fixed on the gear supporting shaft, an operating shaft slidably and revolvably mounted in the bearing frame, a pinion fixed on the operating shaft to engage the gear wheel on the gear supporting 40 shaft, a ratchet gear fixed on the operating shaft, a pawl adapted to engage the ratchet gear whereby said shaft and gears are held against retrograde movement, means to shift the operating shaft whereby 45 the pinion thereon may be disengaged from the gear wheel and the sprocket gears, and springs thereby released, and means actuated by the movement of the operating shaft to shift the sprocket gear on the cranking shaft 50 thereby engaging the clutch member thereon with the clutch member on the engine shaft.

7. In an engine starting mechanism, the combination with the engine shaft, of a 55 clutch member fixed thereon, a cranking shaft having on it a clutch member adapted

to engage the clutch member on the engine shaft whereby the latter may be operated by the cranking shaft, a sprocket gear loosely mounted on the cranking shaft, a clutch member on the sprocket gear to engage the clutch member on the engine shaft whereby the latter is operated by the sprocket gear, a spring normally holding the clutch members on the cranking shaft and sprocket 60 gear out of engagement with the clutch member on the engine shaft, a gear supporting frame, a bearing frame slidably and adjustably mounted in the supporting frame, a gear shaft revolvably mounted in the bearing frame, a sprocket gear fixed on the gear shaft, a sprocket chain to connect the gear with the sprocket gear on the cranking shaft, 65 springs connected to the opposite sides of the chain and adapted to be compressed by the movement of the chain in one direction whereby when the springs are released the force thereof will drive the chain and sprocket gears in the opposite direction, a gear wheel fixed on the gear supporting 70 shaft, a jointed operating shaft slidably and revolvably mounted in the bearing frame, a pinion fixed on the jointed shaft to engage the gear wheel on the gear supporting shaft, a spring to hold the jointed shaft in retracted 75 position and the pinion thereon in engagement with said gear wheel, means to hold the jointed shaft against retrograde movement, an operating wheel arranged on the inner end of said shaft, a knob also arranged on the same end of the shaft whereby the latter is projected against the pressure of the spring thereon to disengage the pinion from the gear wheel thereby releasing 80 the sprocket chains and springs, a clutch shifting lever having an operative engagement at one end with the sprocket gear on the cranking shaft, and adapted to be engaged by the end of the operating shaft when the latter is projected to disengage the 85 pinion and gear wheel whereby the sprocket gear on the cranking shaft is shifted to engage the clutch member thereon with the clutch member on said engine shaft.

In testimony whereof I have hereunto set 90 my hand in presence of two subscribing witnesses.

CHRISTIAN CHRISTIANSEN.
